PLATFORM COVER TURNING MACHINE
Thomas W. Snow, Melrose, and Lawrence A. Severy,
Rockport, Mass., assignors to United Shoe Machinery
Corporation, Boston, Mass., a corporation of New
Jersey

Filed June 25, 1962, Ser. No. 204,836
10 Claims. (Cl. 12—1)

This invention relates to machines for use in the manufacture of shoes, and is herein illustrated as embodied in a machine for turning a platform cover over a platform or midsole of a platform shoe of the type variously referred to as "California," "slip-lasted" or "force-lasted."

In the manufacture of shoes of this type an upper, an insole or sock lining, and a strip of flexible material, known as a "platform cover" or "wrapper," are assembled together off the last, usually by stitching. A pre cemented midsole or platform is thereafter attached to the sock lining, a last inserted into the shoe to shape the shoe, and the cover or wrapper is laid over and secured to the marginal portion of the platform to cover its edge. An outsole is subsequently cement attached to the platform, which sometimes has an integral wedge heel, to complete the shoe.

The cover or wrapper usually hugs the upper rather intimately and, before it can be laid over the platform by the lasting instrumentalities of the lasting machine, must first be turned away from the upper. The operation of turning the cover is often performed after a last has been forced into the shoe. In prior cover turning machines the turning is effected by grippers which engage the margin of the cover at several points and pull it to turn it away from the upper either by movement of the grippers while the shoe is held stationary, or by movement of the shoe relative to the stationary grippers. In either case, such pulling action, unless carefully controlled, subjects the cover strip to stresses which may damage it or even rip it away from the upper and sock lining.

It is an object of the invention to provide a machine for turning the platform cover at the forepart of a shoe after a platform sole has been attached to its sock lining but before insertion of a last, wherein the risks pointed out above are eliminated.

To this end, the machine disclosed herein comprises a form engageable in the interior of the forepart of a shoe to support the shoe while a platform sole is attached to its sock lining, a gage movable into engagement with the toe end of the shoe to permit an operator to register the platform sole with relation to the sock lining, gripper means engageable with the free margin of a platform cover at the toe end of the shoe, a fixed abutment engageable with the platform sole of the shoe when the shoe is moved off the form, wipers engageable between the cover and the upper, and means to impart to the gripper means and the wipers movement in a direction to move the shoe off the form and to cause the wipers to move relative to the shoe after engagement of the platform sole with the fixed abutment to turn to cover away from the upper into a plane substantially normal to the plane of the platform sole.

Preferably, and as herein illustrated, the form is constructed to be expanded laterally within the forepart of the shoe so as to maintain the sock lining taut while a platform sole is attached, and the invention provides means effective to cause the form to be expanded and concomitantly therewith to move the gripper means and the wipers into position to engage the platform cover and the upper, respectively, and additional means effective to cause the form to be contracted after the attachment of the platform sole and concomitantly therewith to render effective the means mentioned above which

2

impart to the gripper means and wipers movement in a direction first to move the shoe off the form and thereafter to cause the wipers to move relative to the shoe while the cover is held gripped by the gripper means to effect the turning of the cover.

These and other novel features of the invention will appear more clearly from the detailed description which follows and will be more particularly pointed out in the claims.

- 10 In the drawings,
FIG. 1 is a view in left side elevation of a platform cover turning machine embodying the invention;
FIG. 2 is a view in front elevation of the machine shown in FIG. 1;
15 FIG. 3 is a plan view of the machine head;
FIG. 4 is a detail perspective view of an equalizing mechanism for controlling the tensioning action of gripper members engageable with a platform cover of a shoe mounted in the machine;
20 FIG. 5 is a plan view, on an enlarged scale and partly broken away, of an expansible form engageable in the interior of the forepart of a shoe to be operated upon;
FIG. 6 is a view in left side elevation, partly in section and on the same scale, of the form shown in FIG. 5;
25 and
FIG. 7 to 10, inclusive, are views in left side elevation illustrating the positions of the operating instrumentalities of the machine at various stages of a cover turning operation.
30 The shoe S to be operated upon in the illustrated machine comprises an upper U (FIGS. 1 and 7 to 10), to the lower margin of which is attached a sock lining L, and a platform cover strip C which, after attachment of a midsole or platform P to the sock lining and insertion
35 of a last, is laid over and secured to the marginal portion of the platform in a cover lasting machine to cover the wall or edge face of the platform sole prior to attachment of an outsole to complete the shoe. Before it can be thus laid and secured to the platform, the cover which as shown in FIGS. 7, 8 and 9 occupies an upstanding position parallel to and in close proximity to the upper, must be turned substantially 180° away from the upper to permit the lasting instrumentalities to tension and wipe it inwardly over the platform.
40 To effect the turning of the platform cover C in the illustrated machine, the operator slips an unlasted shoe over a jack or form, identified generally by the reference character 20 (FIGS. 1, 2, 3, 5, 6 and 9) and comprising an arm 22 which, as viewed from the front of the machine, that is, at the right of FIG. 1, extends upwardly and rearwardly from a base plate 26 and, as shown in FIGS. 3 and 5, terminates in an enlarged, flat and wedge-shaped portion 24 engaged by the forepart of the sock lining of the shoe. The base plate 26 is bolted to the top of a post or frame 28 fixed to a casing 30 rising from the base 32 of the machine. The shoe form or jack 20 also comprises a pair of blocks 34 which, as best shown in FIGS. 3 and 5, are shaped to correspond substantially to the two halves of a divided, laterally expansible shoe form or last and which, when expanded in a manner shortly to be described, stretch the jacked shoe so as to facilitate the attachment of a platform sole to the sock lining. Each block 34 is pivotally secured by a pin 36 to the upper rearwardly extending arm of a substantially U-shaped member 38 which is hingedly mounted for lateral swinging movement relative to the arm 22 on a bolt or pin 40 projecting upwardly from the base plate 26, the opposite sides of the arm 22 being recessed, as shown at 41 in FIG. 6, to accommodate the two members 38. As shown in FIG. 5, each block 34 is recessed or rabbeted at 42 to provide clearance for movement of expansion and contraction of the blocks relative to the tapered rear portion 24 of the

arm 22 as well as for independent swinging movement of each block 34 about its pivotal connection to the member 38 to conform to the contour of the forepart of the shoe after the blocks have reached the limit of lateral expansion within the shoe.

For actuating the members 38 to cause movement of expansion of the blocks 34, the following arrangement is provided. Extending downwardly from the lower, rearwardly extending arm of each member 38 is a pin 44 which is engaged by a roll 46 carried by a pin 48 mounted in the arms of the bifurcated upper end portion of a lever 50 (FIG. 2) pivoted at 52 on a bracket 54 which is fast on the post 28. The lower, bifurcated end of each lever 50 also carries a roll 56. The rolls 56 engage the opposite sides of a cam block 58 mounted for heightwise sliding movement on a bar 60 fixed at its opposite ends to cross members 62, 64 between the spaced uprights of the post 28. The block 58 is connected by a rod 66 to a treadle 68 (FIG. 1) pivoted at 69 on the base 32 of the machine. To the rod 66 is attached one end of a spring 70, the other end of which is anchored to the casing 36, the arrangement being such that the spring maintains the treadle normally in a position intermediate of its upper and lower limits of movement for a purpose which will be explained below.

In the rest position of the machine the rolls 56 on the lower ends of the levers 50 are in engagement with the opposite sides of the upper, wide portion of the cam block 58, whereby the levers are biased in a direction such that the rolls 46 on their upper ends press against the pins 44 to maintain the members 38 close together, as shown in FIG. 3, against the tension of associated springs 72 which tend to cause them to swing away from each other. The spring 72 associated with each member 38 is attached at one of its ends to a pin 73 projecting from the lower, rearwardly extending arm of the member and at its opposite end to a pin 74 projecting downwardly from the base plate 26.

To the treadle 68 is also connected the lower section 75 of a two-part rod 76 (FIG. 1). The upper end of the rod section 75 is threaded into a bifurcated block 78, between the arms of which is mounted a pin 80 to which is connected one end of a link 82, the other end of which is pivoted at 83 to the lower end of an arm 84 depending from a bracket 86 fixed to the cross member 64. Also mounted on the pin 80 is a bifurcated block 88 into which is threaded the lower end of the upper section 90 of the two-part treadle rod 76. The upper end of the rod section 90 is connected to a bell crank lever 92 comprising a rearwardly extending arm 94 and a forwardly extending, longer arm 96. The arm 94 is pivoted on a pin 97 mounted in rearwardly extending parallel arms 98 of a carrier 100 having downwardly extending parallel arms 101 pivoted at their lower ends on a transverse shaft 102 supported in the bracket 86 and upwardly extending parallel arms 103.

Between the upper ends of the spaced parallel arms 103 of the carrier 100 there is provided a block 104 (FIGS. 1, 3 and 7-10) formed with forwardly projecting fingers 106 arranged to contact the outer face of the platform wrapper at opposite sides of the tip of the shoe, when the carrier is caused to swing into operative position in a manner to be described shortly, and to cooperate with complementary fingers 108 adapted to engage the inner face of the cover. The fingers 108 are integral with a pair of parallel arms 110 pivoted at their forward ends on a pin or bolt 112 extending through the block 104. The arms 110 are connected by universal joints 114, rods 116 and universal joints 118 to the opposite ends of a whiffletree 120 (FIGS. 3 and 4) mounted for rocking movement about a bolt 121 extending into the arm 96 of the bell crank lever 92. To the upper surface of the arm 96 is secured by a screw 122 a T-shaped leaf spring member 123, the cross bar of which overlies the whiffletree 120 and tends to maintain it in condition of equilibrium. This arrangement permits

equalizing the tension exerted on the platform cover by the gripper fingers 106 at the opposite sides of the toe end of the shoe.

On each end of the bolt 112 is mounted for rocking movement about the bolt a cam member 124 (FIGS. 1, 3 and 7-10) to which is secured one end of an arm 126 consisting of a strip of flexible metal, such as spring steel. To the other end of each arm 126 is fixed a blade or wiper 128 which, when the carrier 100 is swung in one direction, is moved into a position between the platform cover C and the upper U at the side of the shoe S and which during the reverse swinging movement of the carrier, is moved in a direction to turn the cover from the position shown in FIG. 7 to that shown in FIG. 10. To a pin 130 projecting from each cam member 124 is attached one end of a spring 132, the other end of which is attached to the underside of the adjacent gripper arm 110. In the rest position of the machine the springs 132 maintain the cover turning wipers 128 and the cam members 124 in the positions shown in FIG. 1 in which each cam member is in engagement with a roll 134 (FIGS. 1, 3, 9 and 10) mounted on the forwardly projecting portion of a bracket 136 secured to each of a pair of spaced uprights 138 mounted at their lower ends on the shaft 192 and joined together at their upper ends by a cross member 140. The structure formed by the uprights 138 and the cross member 140 is connected by members 142 to the opposite sides of a bracket or frame 144 secured to the cross member 62. The assembly described above is under the influence of a spring 146 (FIGS. 1, 9 and 10) attached at one end to a pin 148 projecting from the carrier 100 and at its opposite end to a pin 150 projecting from the bar 60, the said spring tending to cause the carrier 100 to swing clockwise from the position shown in FIG. 1 to that shown in FIG. 7. The assembly is held in its retracted position shown in FIG. 1, against the tension of the spring 146, by engagement of a detent 152 (FIG. 1) fixed between the rearwardly extending arms 98 of the carrier 100 with a pawl 154 fast on a rockshaft 156 mounted in the uprights 138. Also fast on the shaft 156 is one end of a link 158, the other end of which is pivotally connected to the lower end of a rod 160 extending through a plate or bracket 162 fixed to the cross member 140. The upper end of the rod 160 is provided with a knob 164 between which and the plate 162 is interposed a spring 166 surrounding the upper end portion of the rod 160.

The operation of the machine thus far described is as follows. The operator mounts the forepart of an unlatched shoe S in inverted position on the jack or form 20 (FIG. 1) comprising the arm 22 with its flat wedge-shaped portion 24 and the blocks 38, which at this time are in the closed or contracted positions. He then presses the knob 164 and, the rod 160 being depressed, the link 158 is caused to swing clockwise and the shaft 156 is rocked in the same direction, disengaging the pawl 154 from the detent 152 and releasing the assembly comprising the carrier 100, on which are mounted the gripper fingers 106, 108 and the cover turning wipers 128, to the action of the spring 146 which causes it to swing in a clockwise direction from the position shown in FIG. 1 to that shown in FIG. 7. When the knob 164 is released, the rod 160 is returned to its initial position by the spring 166 and causes the link 158 to swing in counterclockwise direction to locate the pawl 154 in position to be engaged by the detent 152 to lock the carrier when the treadle 68 is released at the end of a cover turning operation. Movement of the link 158 in that direction is limited by a stop pin 167 (FIG. 1) projecting from one of the bars or uprights 138.

As the assembly is thus unlocked, the treadle 68 which, as previously noted, is held by the spring 70 in an intermediate position when the assembly is locked, is raised by the spring. As the treadle rod 66 moves upward, the

cam block 58 move upward along the slide bar 60 and the opposite inclined sides 58a of its lower portion (see FIG. 2) are engaged by the rolls 56 on the lower ends of the levers 50, which are thereby caused to swing oppositely outward and away from the pins 44 depending from the lower arms of the members 38, so that these members and the blocks 34 carried by them may be swung by the springs 72 in a direction to expand laterally within the forepart of the shoe and support it firmly while the operator attaches a platform to the sock lining.

When the carrier 100 swings clockwise, a toe gage 168 (FIGS. 1 and 7 to 10) is moved into engagement with the toe end of the shoe, the gage projecting somewhat above the level of the sock lining L to enable the operator to locate a platform P on the sock lining. The toe gage 168 forms one arm of an L-shaped lever 170, the other arm 172 of which terminates in a bifurcated block 174 which is fulcrumed on a pin 176 mounted in a lug 177 projecting from the block 104 between the arms 103 of the carrier 100. The lever 170 is normally held in the position shown in FIG. 1 by a tension spring 178 attached at one end to the lever arm 172 and at its opposite end to the pin 143 which projects from the carrier. As the carrier 100 swings from the position shown in FIG. 1 to that shown in FIGS. 7 and 8, the undersurface of the lever arm 172, somewhat to the left of the rounded lower edge of the block 174, is engaged by a roll 189, and the lever 170 is swung clockwise about the pin 176, against the tension of the spring 178, to locate the gage in operative position. The roll 180 is carried by a pin 182 mounted in the bifurcated rear end portion of a block 184 pivoted at its forward end on a pin 186 mounted in the upwardly extending arms of the bracket 144. The block 184 is maintained by a spring 188, which is connected at one end to the block and at its other end to the bracket 144, against the upper end of an adjusting screw 190 threaded through a boss 192 of the bracket 144. By adjustment of the screw 190 the level of the rearward end of the block 184 may be varied so as to vary the extent of clockwise swinging movement of the lever 170 to locate the toe gage 168 in different operative positions according to differences in the sizes of shoes mounted on the form or jack 20. A nut 194 locks the screw 190 in the adjusted position.

Movement of the carrier 100 to the position shown in FIG. 7 moves the fixed upper gripper fingers 106 projecting from the block 104 disposed between the upper ends of the arms 103 of the carrier into engagement with the outer face of the cover strip C, while the lower fingers 108 formed integral with the pivoted arms 110 are moved into a position between the cover and the upper. Also, as the carrier 100 is unlatched and the cam members 124 which carry the cover turning wipers 128 are moved out of engagement with the rolls 134 (FIG. 1), the springs 132, which are attached to the pins 130 on the cam members, swing the cam members in a clockwise direction to locate the wipers in the substantially horizontal position shown in FIG. 7.

The operating instrumentalities of the machine occupying the positions shown on FIG. 7 and the forepart of the shoe being stretched on the form 20, the operator spots and attaches by hand to the sock lining L a pre-cemented platform P, utilizing the gage 168 to register the platform correctly with relation to the sock lining. He next depresses the treadle 68. During the first portion of the downward movement of the treadle, the treadle rod 76 swings the lever 92 about its fulcrum 97 in a clockwise direction to rock the gripper arms 110 counterclockwise, first to the position shown in FIG. 7, to bring the gripper fingers 108 into engagement with the free margin of the cover C at the tip of the shoe, and then to the position shown in FIG. 8. As the arms 110 rock in that direction, they impart, through the pins 130 carried by the cams 124, movement in the same direction to the cams to move the wiper blades 128 from their horizontal

position shown in FIG. 7 to that shown in FIG. 8, where they engage the sides of the shoe, the spring arms 126 to which the blades are secured yielding laterally to enable the blades to accommodate themselves to the width of the shoe.

When the gripper fingers 108 reach the position shown in FIG. 8, with the margin of the cover C at the tip of the shoe engaged between them and the fixed upper gripper fingers 106, the gripper arms 110 and their fingers 108 become rigid with the carrier 100. Thereafter, as the treadle is depressed further, the assembly comprising the carrier 100 and the gripper members is rocked as a unit counterclockwise about the shaft 102, from the position shown in FIG. 8 to that shown in FIG. 9, overcoming the force of the spring 146 which tends to urge the carrier to swing clockwise.

As the treadle is depressed, the treadle rod 66 (FIG. 1) moves the block 58 downward to the position shown in FIG. 2, where the sides of its upper, wider portion are engaged by the rolls 56 on the lower ends of the levers 50, causing the levers to swing oppositely inward to bring the rolls 48 at their upper ends into engagement with the pins 44 carried by the members 38, whereby these members are caused to turn about their pivots 40 (FIG. 1) toward each other to move the blocks 34 from their expanded position shown in FIG. 5 to their original contracted position, so as to release the shoe.

When the carrier 100 is swung away from the position shown in FIG. 8 toward that shown in FIG. 9, the arm 172 of the lever 170 moves off the roll 180 carried by the block 184, and the lever is returned by its spring 178 to its initial position, moving the toe gage 168 away from the shoe.

As the grippers 108, in engagement with the inner face of the cover, are moved with the carrier 100, they pull the shoe off the form 20 in a rearward direction until the wiper cams 124 again engage the rolls 134 and are rocked counterclockwise, as seen in FIG. 9, causing the wipers 128 to turn the shoe in a counterclockwise direction into the substantially vertical position shown in FIG. 10, where the platform P on the shoe engages a fixed abutment 198 secured to a bracket 200 which extends upwardly from a plate 202 fixed to the cross member 140. As the shoe is turned by the wipers while the cover is held clamped between the upper and lower grippers, the margin of the cover at the tip of the shoe is turned outward about 90°.

The shoe now being held by the abutment 198 against further movement, and as the operator continues to depress the treadle, the wipers 128 are moved relative to the shoe to complete the turning of the cover C away from the upper U until it occupies a plane substantially at right angles to the plane of the shoe bottom.

At this point the operator releases the treadle and the carrier 100, which had been moved to a position somewhat further to the left of that shown in FIG. 1, is swung clockwise by its spring 146 until the detent 152 engages the pawl 154 to lock the carrier in its original starting position. During such clockwise movement of the carrier, the arms 110 are caused to swing clockwise to move the grippers 108 to their open position so as to permit the operator to remove the shoe. The clockwise swinging movement of each arm 110 is yieldingly limited by engagement with the underside of the cross member 140 of a leaf spring 204 secured to each arm.

Having described the invention, what we claim as new and desire to secure by Letters Patent of the United States is:

1. In a machine for turning a cover over a platform sole of a partially completed shoe, the combination which comprises:
- a form for supporting a shoe while a platform sole is attached to the sock lining of the shoe,
means engageable with the platform cover at an end of the shoe to grip the cover,

cover turning means engageable with the shoe upper at the sides of the shoe, and

means effective to operate the cover gripping means and the cover turning means first to move the shoe away from the form after attachment of the platform sole and thereafter to cause the cover turning means to move relative to the shoe while the cover is clamped by the gripping means to turn the cover away from the upper and into a plane substantially normal to the plane of the platform sole.

2. In a machine for turning a cover over a platform sole of a shoe, the combination comprising
a form for supporting a shoe while a platform sole is attached to its sock lining,
means for turning the platform cover after attachment of the platform sole including members operative between the cover and the upper,
means effective to cause the cover turning means to move in one direction to locate said cover turning members adjacent the cover and the shoe upper, and other means effective to cause the cover turning means to move in the opposite direction to be located between the cover and shoe upper and then continue to move in said opposite direction first with the shoe to move it off the form and thereafter relative to the shoe to turn the cover away from the upper into a plane substantially normal to the plane of the platform sole.

3. In a machine for turning a cover over a platform sole of a shoe, the combination comprising
a form for supporting a shoe while a platform sole is attached to its sock lining,
means for turning the platform cover after the attachment of the platform sole including members operative between the cover and the upper,
means effective to cause the cover turning means to move in one direction to locate said cover turning members adjacent the cover and the shoe upper, a fixed abutment arranged to be engaged by the platform sole of the shoe, and
other means effective to cause the cover turning means to move in the opposite direction to be located between the cover and shoe upper and then continue to move in said opposite direction first to move the shoe off the form and toward the abutment, and to move relative to the shoe after engagement of its platform sole with the abutment to turn the cover away from the upper into a plane substantially normal to the plane of the platform sole.

4. In a machine for turning a cover over a platform sole of a partially completed shoe, the combination which comprises

a form for supporting a shoe while a platform sole is attached to its sock lining,
grippers engageable with the cover at an end of the shoe on the form and including jaws operative between the cover and the upper,
wipers engageable with the upper at the sides of the shoe,
means for causing movement of the grippers and the wipers first in one direction to locate said wipers and gripper jaws adjacent the cover and the upper before attachment of the platform sole,
operator controlled means to actuate the means which move the grippers and wipers in said one direction, a fixed abutment arranged to be engaged by the platform sole after the shoe is moved off the form, and other operator controlled means to actuate the gripper and wiper moving means after attachment of the platform sole to move the grippers and wipers in the opposite direction to be located between the cover and shoe upper and then continue to move in said opposite direction first with the shoe to move the shoe off the form and into engagement with the abutment, and thereafter to move the wipers relative to the shoe to turn the cover away from the upper and

into a plane substantially normal to the plane of the platform sole.

5. In a machine for turning a cover over a platform sole of a partially completed shoe, the combination which comprises

a form engageable with the interior of the forepart of a shoe to support the shoe while a platform sole is attached to its sock lining,
a gage movable from an inoperative to an operative position into engagement with the toe end of the shoe on the form to permit an operator to locate the platform sole in register with the sock lining,
grippers engageable with the platform cover at the toe end of the shoe and including jaws operative between the cover and the upper,
wipers engageable with the shoe upper at opposite sides of the forepart of the shoe on the form,
means effective to cause the grippers and wipers to move in one direction to locate said wipers and gripper jaws adjacent the platform cover and the upper prior to attachment of the platform sole, operator controlled means to actuate the means which cause the grippers and wipers to move in said one direction,
means effective upon actuation of said operator controlled means to cause movement of the toe gage into operative position,
other operator controlled means effective to cause the grippers and wipers to move in the opposite direction to be located between the cover and shoe upper and then continue to move in said opposite direction to engage the cover and the upper and to move the shoe off the form,
means effective upon actuation of said other operator controlled means to move the toe gage out of engagement with the shoe,
a fixed abutment arranged to be engaged by the platform sole to support the shoe after it has been moved off the form by the grippers and wipers, and
means effective to cause the wipers to move relative to the shoe while the cover is held clamped by the grippers and the shoe is supported by the abutment to turn the cover away from the upper into a plane substantially normal to the plane of the platform sole.

6. In a machine for turning a cover over a platform sole of a partially completed shoe, the combination which comprises

a form engageable with the interior of the forepart of a shoe to support the shoe while a platform sole is attached to its sock lining,
a gage moveable from an inoperative to an operative position into engagement with the toe end of the shoe on the form to permit an operator to locate the platform sole in register with the sock lining,
grippers engageable with the platform cover at the toe end of the shoe and including jaws operative between the cover and the upper,
wipers engageable with the shoe upper at opposite sides of the forepart of the shoe on the form,
a carrier mounting the toe gage, grippers and wipers, means normally locking the carrier in a retracted position,
operator controlled means for unlocking the carrier, means effective upon unlocking of the carrier to move it in one direction toward the shoe on the form, means effective upon movement of the carrier in said one direction to move the gage into engagement with the end of the shoe and to move the grippers and wipers so as to locate said wiper and gripper jaws adjacent the cover and the upper,
a fixed abutment arranged to be engaged by the platform sole of the shoe when the shoe is moved off the form,
other operator controlled means for first causing the grippers to be moved into engagement with the free

margin of the cover and the wipers to move into engagement with the upper and thereafter to cause movement of the carrier, together with the grippers and wipers, in the opposite direction to be located between the cover and shoe upper and then continue to move in said opposite direction to move the shoe off the form and toward the fixed abutment, and

means effective after engagement of the shoe with the abutment to move the wipers relative to the shoe to turn the cover away from the upper into a plane substantially normal to the plane of the platform sole.

7. In a machine for turning over a platform sole a cover strip assembled with an upper and a sock lining of a platform shoe, the combination comprising

a laterally expandible form engageable in the interior of the forepart of a shoe to support the shoe while a platform sole is attached to its sock lining,

means normally maintaining the form contracted to facilitate the mounting of a shoe thereon,

manual means to actuate said means to cause lateral expansion of the form prior to attachment of a platform sole,

cover clamping and cover turning means also actuated by operation of said manual means to engage respectively the free margin of the cover at the toe end of the shoe and the upper at the opposite sides of the forepart of the shoe, and

other manual means the operation of which is effective to cause the form to be contracted to permit removal of the shoe after attachment of the platform sole and also effective first to cause the cover clamping and cover turning means to move the shoe off the form and thereafter to cause the cover turning means to move relative to the shoe to turn the cover outward away from the upper into a plane substantially normal to the platform sole.

8. A machine according to claim 7, wherein the shoe supporting form comprises

a fixed arm having a portion engageable within the forepart of a shoe,

a member adjacent the fixed arm at either side thereof and pivoted for lateral movement relative to the arm, and

a block mounted on each member and shaped to conform to the curvature of the shoe.

9. A machine according to claim 8, wherein each block is pivotally mounted for independent swinging movement after expansion of the form within the shoe to accommodate itself to the curvature of the shoe.

5 10. In a machine for turning over a platform sole a cover assembled with an upper and sock lining of a platform shoe, the combination which comprises

a laterally expandible form engageable in the interior of the forepart of a shoe to support the shoe while a platform sole is attached to its sock lining, grippers engageable with the cover at the toe end of the shoe and including jaws operative between the cover and the upper,

wipers engageable with the upper at the opposite sides of the forepart of the shoe,

a carrier mounting the grippers and wipers, means maintaining the carrier in a retracted position

away from the form and the form contracted to facilitate the mounting of a shoe thereon,

manual means to actuate the said means to cause the form to be expanded laterally within the shoe and the carrier to move in one direction toward the form to cause said gripper jaws and wipers to be located adjacent the cover and the upper,

other manual means to actuate the said means to cause the shoe form to be contracted after attachment of a platform sole,

means also actuated by said other manual means to cause the carrier to move in the opposite direction away from the form and the grippers and wipers to be located between the cover and shoe upper and then continue to move in said opposite direction to move the shoe off the form,

a fixed abutment arranged to be engaged by the platform sole as the shoe is moved by the grippers and wipers, and

means effective upon engagement of the platform sole with the abutment to cause the wipers to move relative to the shoe to turn the cover outward away from the upper into a plane substantially normal to the plane of the platform sole.
